PAINTING MACHINE

Howard V. Schweitzer, Cleveland, Ohio

Application September 7, 1939, Serial No. 293,794

20 Claims.

(Cl. 91—45)

This invention relates to painting machines and more particularly to a machine adapted to paint automobile wheels, or the like, with enamel or other coating material.

Heretofore, automobile wheels have been painted by skilled spray gun operators who worked within conventional spray booths. Such painting operations are expensive because they are hand operations, and because considerable quantities of paint are wasted inevitably by the operators. Further, the paint spray which is not applied to the wheels tends to settle upon everything near the spray guns and constitutes a serious operating and maintenance problem. This operating and maintenance problem is especially serious when enamels are used, since the resin in the waste enamel spray tends to deposit on all surfaces near the spray guns, forming small stalactites or stalagmites which are difficult to remove. Also, because the spray gun operators work in an atmosphere laden with spray, the working conditions are apt to be deleterious to the operator's health.

It is a principal object of this invention to provide a machine which paints automobile wheels and the like, and which substantially eliminates the hand operations employed heretofore, thereby greatly reducing the expense of painting automobile wheels. It is another object of this invention to provide a machine which substantially eliminates the waste of paint spray by applying almost all of the paint employed directly to the objects to be painted.

A further object of this invention is to provide a machine which eliminates the production and maintenance problem incurred in the deposit of waste spray by recovering substantially all of the paint or enamel spray which is not applied to the objects to be painted. A still further object of this invention is to provide a machine in which the operators work in an uncontaminated atmosphere, thereby providing healthful working conditions and increasing the efficiency of the operators.

Other and further objects and advantages of this invention will be manifest in the following specification, claims, and drawings, in which:

Fig. 1 is a plan view having a portion broken away to show the arrangement of a portion of the operating mechanism;

Fig. 2 is a partial section in elevation taken along line 2—2 of Fig. 1;

Fig. 3 is an enlarged fragmentary sectional detail taken from Fig. 2;

Fig. 4 is a detailed elevation of cam drive mechanism;

Fig. 5 is a detailed plan of the cams and air valve;

Fig. 6 is a diagrammatic flow sheet showing

the wash, water, and exhaust air circulating systems, and

Fig. 7 is a diagrammatic flow sheet showing the flow and control of the spray gun control air.

5 In the drawings, in which like reference characters refer to like parts, 10 represents a suitable structural steel framework which supports the machine. A pair of channel beams 11 and 12 carry a pair of thrust bearings 13 and 14, respectively, in which is journaled a main vertical shaft 15. Mounted upon and fixed to the shaft 15 is the hub 21 of the main spindle turret 20, having suitable truss-shaped spokes 22 which support the rim 23. A conical cover sheet 24, having a depending eave 25, extends over the spokes 22 and the rim 23 to provide a suitable surface for the turret 20.

The turret 20 is driven by a motor 30 through a variable speed reducer 31. Mounted on the turret drive shaft 32 of the speed reducer 31 is a sprocket, pinion 33 which drives a suitably toothed sprocket ring 34 by means of a chain 35, the ratio of the number of teeth in the sprocket pinion to the number of teeth in the sprocket ring being a whole number. A suitable take-up for the chain 35 is provided by the idler sprocket 36. The motor 30, variable speed reducer 31, and idler sprocket 36 are preferably mounted upon the framework 10, and the sprocket ring 34 is suitably supported on the under surface of the turret 20.

35 The rim 23 carries a plurality of vertical spindles 40 suitably spaced about the periphery of the turret 20, the number of spindles 40 being equal to, in the preferred embodiment disclosed, or a multiple or aliquot fraction of, in modified forms of this invention, the whole number which is the ratio between the sprocket pinion 33 and sprocket ring 34. Each spindle 40 is comprised 40 of a sleeve 41 which is fixed to the rim 23 and in which is journaled a spindle shaft 42. A sleeve cap 43, fixed to the spindle shaft 42, covers the portion of the sleeve 41 which extends above the surface of the turret 20. Removably mounted on the upper end of the spindle shaft 42 is a wheel chuck 44 comprised of a shaft sleeve 45 which engages the shaft 42 and which carries a conical center 46 and dog 47 adapted to engage the hub of a wheel placed upon the chuck. A V-belt pulley 48 is fixed on the lower end of the spindle shaft 42.

45 Each of the spindles 40 is driven during a portion of the travel of the turret 20 by a spindle drive unit 50, comprising a motor and variable speed reducer, which may be carried by the frame 10. A flat pulley 51 mounted on the drive shaft of the variable speed reducer of the drive unit 50, engages the flat back of the V-belt 52, which is also supported by the main adjustable idler 53 and the fixed idlers 54 mounted on the frame

16. As the turret 20 is rotated, the V-belt pulleys 48 of the spindles 40 engage the V surface of the V-belt 52, which, being under tension and tending to assume the position of a chord between the drive pulley 51 and the idler 53, drive the spindles at a speed which is the sum of the peripheral speed of the turret 20 and the lineal speed of the belt 52.

The spindles 40 may be driven similarly during another portion of the travel of the turret 20 by a second drive unit 60, drive pulley 61, V-belt 62, adjustable idler 63 and fixed idler 64.

Carriage and carriage drive

Located on the frame 10 beyond the periphery of the turret 20 and adjacent the spindle V-belt 52 is a carriage 70 which is adapted to travel in the arcuate carriage track 71 which is centered upon the main shaft 15. The carriage 70 carries a pair of spray gun posts 72 and 73 on which are mounted the paint spray guns 74, 75, 76, and 77. A second carriage 80 is located on the frame 10 adjacent the spindle V-belt 62 and is adapted to travel in an arcuate carriage track 81 which is also centered upon the main shaft 15. The carriage 80 carries a spray gun post 82 on which are mounted paint spray guns 84 and 85.

The carriages 70 and 80 are oscillated in the tracks 71 and 81, respectively, by a spider 90, which is rotatably mounted on a suitable bearing 91 located on the main shaft 15 between the channel beams 11 and 12. The spider 90 is comprised essentially of the radial carriage arms 92 and 93 which are connected to the carriages 70 and 80, respectively, a tie rod 94 which connects and spaces the arms 92 and 93, and a cam follower 95 mounted upon the tie rod 94 and arm 92. The angularity of the carriage arms 92 and 93 may obviously be fixed by the tie rod 94 at any suitable angle, which, however, is preferably equal to the angle between radii drawn from the center of shaft 15 through centers of suitably spaced spindles 40, as is shown in Fig. 1.

The spider 90 and the carriages 70 and 80 connected thereto are oscillated about the main shaft 15 by a carriage cam 100 which is keyed on the turret drive shaft 32 and which engages the roller 96 of the cam follower 95. The tension spring 97, connecting the spider 90 to the frame 10, maintains the roller 96 in constant engagement with the cam 100. In order to absorb the shock of the return oscillations of the spider 90 upon the cam 100, an air cylinder and piston shock absorber 98 having an adjustable air release needle valve 99 is provided between the spider 90 and the frame 10.

The cam 100 is provided with a spiral displacement surface 101 extending from point *a* to point *b* and a quick return surface 102 extending from point *b* to point *a*, as shown in Fig. 5, the displacement angle of the cam being approximately 270° and the return angle being, of course, approximately 90°. The spiral displacement surface 101 of the cam is so designed that the rate of displacement of the cam follower 95 is constant, and the corresponding speed of oscillation of the spider 90 and carriages 70 and 80 in the direction of rotation of the turret 20 is equal to the rotational speed of the turret 20. The contour of the quick return surface is not of especial importance since the inertia of the spider 90 and carriages 70 and 80 tend to cause the roller 96 to jump from the quick return surface; the air release needle valve 99 of the shock absorber 98, however, should be so regulated that the return

movement of the cam follower 95 substantially ceases at the instant the roller 96 engages the initial point of displacement *a* of the displacement surface 101. Thus, the smooth operation of the entire carriage mechanism is assured.

Carriage operation

From the foregoing and from Fig. 1, which shows the carriages 70 and 80 at the midpoint of displacement, it is apparent that at the beginning of the displacement, the carriages 70 and 80 are each aligned with a spindle 40 and continue in alignment with that spindle through the period of displacement of the carriages. The carriages then quickly return to starting point of their travel where they are again in alignment with the next succeeding spindles. The substantial synchronization of the paint spray guns with the peripheral travel of the objects to be painted is essential to the successful operation of this invention. This result is obtained in the embodiment disclosed from the fact that the number of spindles 40 carried by the turret 20 is equal to the ratio between the driving sprocket pinion 33 and the driven sprocket ring 34 of the turret drive. Thus, by indexing the cam 100 on the drive shaft 32 so that the carriages are aligned with a spindle at the beginning of displacement, with each succeeding revolution of the cam 100, the carriages move in synchronized displacement with each succeeding spindle. Of course, if the present embodiment is modified so that the number of spindles is an aliquot fraction of the turret drive ratio, synchronization may be obtained by providing a corresponding dwell in the carriage cam, or if the number of spindles is a multiple of the turret drive ratio, synchronization may be obtained by correspondingly multiplying the carriage cam.

Spray guns

The spray guns 74, 75, 76, 77, and 84, 85 carried by the carriages 70 and 80, respectively, are suitably directed toward the spindles with which the carriages are aligned and are supplied with the necessary compressed air from a compressor 110 (not shown except as indicated diagrammatically in Fig. 7) and paint from tanks 111 (not shown except as indicated diagrammatically in Fig. 7). Since the spray guns are responsive to the air supplied thereto, the operation of the spray guns is automatically controlled by the "on" and "off" cam 120 which is mounted on the turret drive shaft 32 and which operates the spray guns by engaging the lever arm 112 of the air valve 113. As is shown in Fig. 5, the "on" and "off" cam 120 is comprised of an "on" segment 121 and an "off" segment 122, each of which are angularly adjustable with respect to each other and cam 100 about the turret drive shaft 32.

The operation of the paint spray guns and the operating air system, as is shown diagrammatically in Fig. 7, is as follows: Air from the compressor 110 flows through the line 114 to the spray guns 74, 75, 76, 77 and 84, 85 when the valve 113 is opened by the engagement of the cam 120 with the lever arm 112, so that the spray guns are then operated. When the cam 120 no longer engages the lever arm 112, the operation of the spray guns stops. Air from the compressor 110 may, of course, be supplied independently to other hand operated guns, as for example, the gun 115 illustrated diagrammatically in Fig. 7, and the operation of the

several spray guns may be further regulated and controlled by any other suitable valves (not shown). The function of the "on" and "off" cam 120 is to control and time the operation of the spray guns 74, 75, 76, 77, and 84, 85 so that the guns are in operation only when the carriages 70 and 80 are being displaced in synchronism with the turret 20. Due to the inertia of the carriages 70 and 80, and spider 90, the carriages are not displaced in synchronism with the turret 20 until a slight period of time after displacement has commenced. Therefore, as shown in Fig. 5, the "on" segment 121 is adjusted on the shaft 32 so that initial point of engagement *a* on the segment 121 lags behind the initial point of displacement *a* on the cam 100 by a suitable period of time, the lag angle between the points *a* and *d* being indicated as the angle ϕ . The length of time the spray guns are operated is determined by the angularity of the "on" segment 121 with respect to the "off" segment 122 as indicated by the angle ω . The length of time the guns are in operation is primarily dependent upon the amount of paint to be sprayed, but in any event, in order to assure that the paint is sprayed upon the object at the angle intended, the guns should be shut off before the displacement of the carriage is completed. Thus, the end point of engagement *e* on the "off" segment 122 should precede the end point of displacement *b* on the cam 100, the angle of advance between the points *e* and *b* being indicated as the angle θ . By so timing and controlling the spray guns the precise application of paint is assured and paint losses due to waste spray are reduced to a minimum.

Booths.

In order to afford proper working conditions and eliminate the production and maintenance problem caused by the deposit of waste paint spray and also to effect a paint economy by recovering waste spray, all spray operations are conducted in booths which, in the preferred embodiment of this invention, are an integral part of the machine. The spraying operations from the carriage 70 are conducted in booth A, and the spraying operations from the carriage 80 are conducted in the booth C. Another booth B may be provided to permit hand spraying operations, as, for example, with a hand spray gun 115, to be conducted. The booths A, B, and C may be disposed about the turret 20 and are supported by the frame 10 in a suitable manner. A guard rail 125 may be provided between the booths to prevent the operators from coming in contact with the turret 20.

Since the construction, operation, and co-operation of each of the booths is preferably similar, the following description of booth C, shown in section in Figs. 2 and 3, will suffice to describe all the booths. The booth C is located above the periphery of the turret 20 and is provided with a ceiling 130 and side walls 131 which are directed inwardly toward the center of the machine and which have suitable openings to permit the entrance and exit of the spindles 40, and the wheels carried thereby. The front of the booth is, of course, open. The rear wall of the booth is an apron 132 of suitably contoured sheet metal which extends between the side walls 131 and slopes downwardly from a position near the ceiling 130, where an outlet for the booth is thus provided, toward the rim of the turret 20. The contour of the apron 132 is substan-

tially conical adjacent its lower edge 133, which closely overlies the cover sheet 24 adjacent the spindles 40; the contour of the apron 132 adjacent its upper edge 134, however, is substantially cylindrical, the change in contour of the apron between its upper and lower edges being made smoothly and without noticeable breaks. A small vertical wall extends across the apron 132 adjacent its upper edge 134 to provide a trough 135 which is supplied with water by the supply pipe 136; the edge of the trough 135 being slightly lower than the edge 134 so that the overflow from the trough will flow in a smooth sheet over the trough wall and a apron 132. A floor trough 137 adapted to receive the water which flows over the cover sheet 24 and eave 25 of the turret 20 is located at the front of the booth, the eave 25 overhanging the inner edge 138 of the trough 137. A drain 139 (not shown, except as indicated diagrammatically in Fig. 6) is connected to the upper portion of the trough 137 so that the trough is normally full of water.

All of the booths A, B, and C are connected to a wash tower 140 in which are located suitable baffle units 141 and 142 between which are located water sprays 143. Access to the interior of the tower 140 may be had through the door 144. Below the baffle unit 142 and overhanging the outlets of the several booths is an eave 145. A catch basin 146 is located below the eave 145 and the booth outlets, from which water is removed by a drain 147. Air is exhausted from the tower 140 through an exhaust outlet 148, located above the baffle unit 141 by a suitable exhaust fan 149 (not shown except as indicated diagrammatically in Fig. 6).

Booth operation.

From the foregoing and from the flow sheet illustrated in Fig. 6, it is apparent that the operation of the washer tower and booths and the wash water and exhaust air systems is as follows: Clean wash water from the pump 150 is supplied through the line 136 to the trough 135, from which the water overflows in a smooth, unbroken sheet, acting as a liquid conveyor 151 which extends over the apron 132, cover sheet 24, and eave 25 into the trough 137 which normally presents an entirely liquid surface that is substantially a continuation of the liquid conveyor 151. Water from the trough 137 is returned to the sump 152 through the drain 139. The sump baffles 153 separate the resin or similar paint residue from the drained fluid conveyor water and the clean water is returned to the pump 150. Wash water is also supplied by the pump 150 to the sprays by the line 154. The baffle unit 142 distributes the spray water within the tower 140. The spray water in the center of the tower falls directly into the catch basin 146, but the spray water near the walls of the tower collects on the eave 145, thereby forming a thin curtain of water 155 which covers the outlets of the several booths and falls into the basin 146. Water from the basin 146 returns through the drain 147 to the sump 152, where the baffles 153 separate the resin from the wash water. The exhaust air enters through the front of the booth where it picks up all of the wasted paint spray. A substantial portion of the waste paint settles out of the exhaust air upon the liquid conveyor 151 or is removed from the air as it comes in contact with the conveyor 151. Almost all of the remainder of the paint is removed from the air as it passes

through the water curtain 155 in moving from the booths into the tower 140. By the time the air has moved upwardly through the water spray and baffle unit 142 in the tower, the paint is substantially removed; the baffle unit 141 serves merely as a means for removing the entrained water from the exhaust air, which is then exhausted from the tower by the exhaust fan 149 through the outlet 148. Since substantially the only surfaces upon which the waste paint can be deposited are the fluid conveyor 151 or surface washed by the spray water, the problem of deposited waste paint spray is eliminated. Furthermore, since substantially all the waste paint is recovered as residue in the sump, which residue may be reworked, a substantial paint economy is afforded by this invention.

Summary of operation

Since the operation of the principal elements of this invention have been described in the foregoing description of the construction of the preferred embodiment of the invention, the general operations of this machine may be described briefly as follows: Since the turret 20 is shown as being rotated in a counter-clockwise direction by the turret drive, the loading station for the machine is located adjacent and to the left of booth A, where an operator places wheels to be painted upon the spindle chucks 44.

As the wheel is carried into the booth A, the spindle pulley 48 engages the moving V-belt 52, thereby rotating the spindle 40, the speed of rotation of the spindle 40 being entirely independent of the rotational speed of the turret, since the speed and direction of the V-belt may be varied at will. As the spindle moves through the booth, the carriage 70, driven by the carriage cam 190 through the spider 90, is aligned with the spindle and is displaced from its initial position in synchronism with the rotation of the turret. When the movement of the carriage is completely synchronized with the movement of the turret, the spray guns are operated by the "on" and "off" cam 120. Each of the spray guns is accurately directed toward a particular surface of the wheel to be painted, so that a minimum of paint is wasted and whatever paint that may not be applied to the wheel is recovered by the fluid conveyor 151 and the water spray and curtain 155 in the tower 140. In the machine described herein, the guns 74 and 75 apply paint to the rim of the wheel, and the guns 76 and 77 apply paint to the under surface of the wheel. As the carriage 70 nears the end of its displacement, the spray guns are cut off and the carriage returns to its initial position for the succeeding spindle, the particular spindle in question moving out of booth A and into booth B. It should be pointed out here that while the movement of the carriage 70 and the operation of the spray guns are accurately synchronized with the movement of the turret, the carriage is driven independently of the turret and the turret is not subjected to accelerating and decelerating loads caused by the oscillations of the carriage.

If the outside of the wheel is to be painted in two colors, one color is preferably applied by a hand operated spray gun in booth B, where a mask may then be dropped over the portion of the wheel painted by the hand operated gun. Such a mask may barely clear the surface of the wheel, so that the freshly painted surface is not marred by the mask.

From booth B the spindle is carried to booth

C, where the automatic operation of the spindles, carriage 80 and spray guns 84 and 85 duplicate the automatic operations in booth A, except that the guns 84 and 85 are directed toward the upper or outside surface of the wheel. The direction of the spray from the guns may be maintained so accurately that the line between the masked and unmasked colors is extremely sharp.

After leaving booth C, the spindle passes to 10 the unloading station, where the painted wheel is removed from the machine. The loading and unloading stations are preferably located adjacent each other so that if the turret is rotated slowly, i. e., about half-speed, by properly setting 15 the speed reducer 31, the machine may be loaded and unloaded by one operator. Of course, if the turret is run at full speed, two operators must be employed to load and unload.

While this description has been of the preferred embodiment of this invention, this invention is not limited to the embodiment described, but may obviously be modified in many respects. For example, in addition to the several modifications pointed out already, the 25 location of the spray guns and the booths with respect to the center of the machine might readily be reversed, and the turret 20 need not be a table mounted upon a central shaft; a ring type turret mounted upon a track and driven by a pinion 30 might well be employed. Further, the particular arrangement of the booths is not essential and the arrangement of the baffles and sprays in the washer tower may be modified. This invention, therefore, is not limited to the embodiment 35 disclosed, either wholly or in part, but is limited only by the following claims.

What is claimed is:

1. In a machine of the class described, a plurality of article supporting means, an endless conveying means for said article supporting means, a carriage movable in synchronism with said conveyor, coating means carried by said carriage, means for operating said coating means during the synchronous movement of said carriage with 40 said conveyor, a booth having an entrance and outlet substantially enclosing said carriage and coating means, a contoured end wall in said booth, means providing a liquid conveyor moving over said end wall and said conveyor, a spray chamber connected to the exit of said booth, means within said spray chamber for forming a curtain of wash water across said booth exit, and means causing a current of air to pass through 45 said booth and spray chamber, whereby substantially all of the waste coating material discharged by said coating means is recovered by said liquid conveyor and wash water.

2. In a machine of the class described, a plurality of article supporting means, an endless conveying means for said article supporting means, a carriage movable in synchronism with said conveyor, coating means carried by said carriage, a booth having an entrance and outlet substantially enclosing said carriage and coating means, means providing a contoured end wall in 50 said booth, a liquid conveyor moving over said end wall, a spray chamber connected to the exit of said booth, means within said spray chamber for forming a curtain of wash water across said 55 booth exit, and means causing a current of air to pass through said booth and spray chamber, whereby substantially all of the waste coating material discharged by said coating means is recovered by said liquid conveyor and wash water.

3. A machine of the class described comprising

an article conveyor, spray guns for spraying coating material on articles carried by said conveyor, a first means for driving said conveyor and spray guns in alternate periods of relative movement and no relative movement between said conveyor and said spray guns, said conveyor moving in a fixed path constantly spaced from said spray guns, and a second means independent of said conveyor and operatively connected with said first means for operating said spray guns only when no relative movement exists between said spray guns and said article conveyor, said spray gun operating means comprising a control valve for said spray guns and a valve operating cam mechanism driven by said means for intermittently moving said conveyor and spray guns relatively with respect to each other, in which the means for driving said conveyor and spray guns comprises a motor, a drive shaft driven by said motor, means for positively driving said conveyor mounted on said drive shaft and a first cam mounted on said drive shaft for moving said spray guns independently of said conveyor, and the spray gun operating means comprises a spray gun control valve, a second valve cam mounted on said drive shaft and a valve cam follower which actuates said control valve, said first cam and said second valve cam being indexed on said drive shaft with respect to each other so that said cam follower actuates said control valve only when said conveyor is not moving relatively to said spray guns.

4. In a machine of the class described, a conveyor, a spray gun carriage, a frame supporting said conveyor and carriage, means for driving said conveyor, a carriage drive member, comprising a cam driven by said conveyor driving means and having a spiral displacement surface and a return surface, said displacement surface being positively engaged with said carriage drive member to periodically displace said carriage synchronously with said conveyor.

5. In a machine of the class described, a conveyor, a spray gun carriage, a frame supporting said conveyor and carriage, means for driving said conveyor, a carriage drive member, comprising a cam driven by said conveyor driving means and having a spiral displacement surface and a return surface, said displacement surface being positively engaged with said carriage drive member to periodically displace said carriage synchronously with said conveyor, means for returning said carriage from its position of maximum displacement to its position of initial displacement, said means operating independently of said return surface on said cam.

6. In a machine of the class described, a conveyor, a spray gun carriage, a frame supporting said conveyor and carriage, means for driving said conveyor, a carriage drive member, comprising a cam driven by said conveyor driving means and having a spiral displacement surface and a return surface, said displacement surface being positively engaged with said carriage drive member to periodically displace said carriage synchronously with said conveyor, means for returning said carriage from its position of maximum displacement to its position of initial displacement, said means operating independently of said return surface on said cam, and means for controlling said carriage return means so that said carriage returns to its position of initial displacement and relative movement between said carriage and said frame substantially ceases at

the instant the spiral displacement surface of said cam engages said carriage drive member.

7. A machine as claimed in claim 5 in which said carriage return means comprises a spring connecting said carriage to said frame, and said carriage return control means comprises an air piston and cylinder and an adjustable air relief valve on said cylinder to control the release of air compressed in said cylinder by said piston.

8. In a machine of the class described, the combination of a rotating turret, driving means for said turret, article supporting means carried by said turret, coating means, and means independent of said turret for driving said coating means to oscillate said coating means around said turret and in synchronism with said turret during one phase of the oscillation of said coating means.

9. In a machine of the class described, the combination of a rotating turret, driving means for said turret, article supporting means carried by said turret, coating means, means independent of said turret for driving said coating means to oscillate said coating means around said turret and in synchronism with said turret during one phase of the oscillation of said coating means, and means independent of said turret for operating said coating means while said coating means move in synchronism with said turret.

10. In a machine of the class described, the combination of a rotating turret, means for driving said turret comprising a driving member and a driven member, the ratio between the driving and driven members of said driving means being a whole number, a plurality of article supporting means mounted on said turret, the number of said article supporting means being an aliquot proportion of said ratio of said driving means, means for rotating said article supporting means independently of said turret, coating means, means independent of said turret for displacing said coating means around said turret in the direction of rotation of said turret and in synchronism therewith, means for operating said coating means while said coating means is displaced around and in synchronism with said turret, and means for recovering waste coating material discharged by said coating means comprising a booth adjacent the periphery of said turret, a floor in said booth, and means providing a liquid conveyor flowing across the floor of said booth and the periphery of said turret.

11. In a machine of the class described, the combination of a rotating turret, means for driving said turret comprising a driving member and a driven member, the ratio between the driving and driven members of said driving means being a whole number, a plurality of article supporting means mounted on said turret, the number of said article supporting means being an aliquot proportion of said ratio of said driving means, means for rotating said article supporting means independently of said turret, coating means, means independent of said turret for displacing said coating means around said turret in the direction of rotation of said turret and in synchronism therewith, and means for recovering waste coating material discharged by said coating means comprising a booth adjacent the periphery of said turret, a floor in said booth, and means providing a liquid conveyor flowing across the floor of said booth and the periphery of said turret.

12. In a machine of the class described, the combination of a rotating turret, means for driving said turret comprising a driving member and

a driven member, the ratio between the driving and driven members of said driving means being a whole number, a plurality of article supporting means mounted on said turret, the number of said article supporting means being an aliquot proportion of said ratio of said driving means, means for rotating said article supporting means, coating means, means independent of said turret for displacing said coating means in the direction of rotation of said turret and in synchronism therewith, and means for recovering waste coating material discharged by said coating means comprising a booth adjacent the periphery of said turret, a floor in said booth, and means providing a liquid conveyor flowing across the floor of said booth and the periphery of said turret.

13. In a machine of the class described, the combination of a rotating turret, driving means for said turret, article supporting means carried by said turret, coating means, means to oscillate said coating means around said turret and moving during one phase of oscillation in synchronism with said turret, and means for operating said coating means while said coating means move in synchronism with said turret, a booth within which said coating means are operated, said booth being located adjacent the periphery of said turret and means providing a liquid conveyor which moves from within said booth and over a portion of said turret on which said article supporting means are carried to recover wasted coating material discharged by said coating means.

14. In a machine of the class described, a booth, an article conveying means movable through said booth, a coating means operating within said booth, means to move said coating means in the direction of travel of said conveying means through said booth and in synchronism with said article conveying means, and means providing a liquid conveyor which moves from within said booth and over said article conveying means to recover a portion of the waste coating material discharged by said coating means.

15. In a machine of the class described, a booth having an exhaust outlet, an article conveying means movable through said booth, a coating means operating within said booth, means to move said coating means in the direction of travel and in synchronism with said article conveying means, means providing a liquid conveyor which moves within said booth and over said article conveying means to recover a portion of the waste coating material discharged by said coating means, and a spray chamber to recover substantially the remainder of the coating material not recovered by said liquid conveyor, said spray chamber being connected to the exhaust outlet of said booth.

16. In a machine of the class described, a booth having an exhaust outlet, an article conveying means movable through said booth, a coating means operating within said booth, means to move said coating means in the direction of travel and in synchronism with said article conveying means, means providing a liquid conveyor moving within said booth and over said article conveying means to recover a portion of the waste coating material discharged by said coating means, and a spray chamber to recover substantially the remainder of the coating material not recovered by said liquid conveyor, said spray

chamber being connected to the exhaust outlet of said booth and including means for spraying a washing medium and means for collecting a portion of said medium to form a washing curtain across the exhaust outlet of said booth.

5 17. In a machine of the class described, a booth having an exhaust outlet, an article conveying means movable through said booth, a coating means operating within said booth, means providing a liquid conveyor which moves within said booth and over said article conveying means to recover a portion of the waste coating material discharged by said coating means, and a spray chamber to recover substantially the remainder 10 15 of the coating material not recovered by said liquid conveyor, said spray chamber being connected to the exhaust outlet of said booth.

18. In a machine of the class described, a booth having an exhaust outlet, an article conveying means movable through said booth, a coating means operating within said booth, means providing a liquid conveyor moving within said booth and over said article conveying means to recover a portion of the waste coating material discharged by said coating means, and a spray chamber to recover substantially the remainder 20 25 30 of the coating material not recovered by said liquid conveyor, said spray chamber being connected to the exhaust outlet of said booth and including means for spraying a washing medium and means for collecting a portion of said medium to form a washing curtain across the exhaust outlet of said booth.

19. In a machine of the class described in which 35 40 45 conveyed articles are coated with spray guns, the subcombination comprising a spray booth having an opening in front and an exhaust opening located rearwardly of the front opening, a floor in said booth sloping downwardly and forwardly toward the opening, an article conveying means movable across the opening in said booth beneath the forward edge of said floor, a collecting trough beneath said conveyor, and means to discharge liquid in a sheet on said floor, thereby providing a liquid conveyor washing over said floor and conveyor and into said trough to convey into said collecting trough waste coating material which, but for the conveyor, would be discharged onto said floor and conveyor.

50 20. In a machine of the class described in which 45 50 55 60 65 70 conveyed articles are coated with spray guns, a spray booth having an opening in front and an exhaust opening located rearwardly of the front opening, a floor in said booth sloping downwardly from a location adjacent the exhaust opening toward the front opening, a turret conveyor, article supporting means carried by said turret adjacent its periphery, a cover sheet having a conical contour and covering the peripheral margin of said turret, said article supporting means extending upwardly through said cover sheet, said floor and cover sheet being located with respect to each other so that said cover sheet extends under the forward edge of said floor, a collecting trough under said cover sheet, and means adjacent the exhaust opening to flow liquid in a sheet on said floor, whereby a liquid conveyor is provided to wash over said floor and cover sheet into said trough to convey waste coating material which would, in the absence of said liquid conveyor, be discharged upon said floor.

HOWARD V. SCHWEITZER.
